US0D1105841S

(12) **United States Design Patent** (10) **Patent No.:** **US D1,105,841 S**
(45) **Date of Patent:** **** Dec. 16, 2025**

(54) **BOTTLE LID**

(71) Applicant: **Everich And Tomic Housewares Co., Ltd**, ZheJiang (CN)

(72) Inventor: **Huajun Yao**, Hangzhou (CN)

(73) Assignee: **EVERICH AND TOMIC HOUSEWARES CO., LTD**, HangZhou (CN)

(**) Term: **15 Years**

(21) Appl. No.: **29/872,715**

(22) Filed: **Mar. 17, 2023**

(30) **Foreign Application Priority Data**

Sep. 20, 2022 (CN) 202230620402.7

(51) **LOC (15) Cl.** **07-02**

(52) **U.S. Cl.**

Primary Examiner — S. Bryan Reinholdt, Jr.

(57) **CLAIM**

The ornamental design for a bottle lid, as shown and described.

DESCRIPTION

FIG. 1 is a front, top perspective view of a bottle lid, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the bottle lid that form no part of the claimed design.

1 Claim, 8 Drawing Sheets
